INVENTOR.
JOHN A. ANDERSON
BY A.B. Bournaw
ATTORNEY

UNITED STATES PATENT OFFICE.

JOHN A. ANDERSON, OF SHERMAN, CALIFORNIA.

GARAGE-DOOR-CONTROL APPARATUS.

Application filed June 24, 1926. Serial No. 118,187.

My invention relates to a garage door control apparatus, and the objects of my invention are; first, to provide an apparatus of this class which will hold the doors securely in open position; second, to provide an apparatus of this class in which when one of the doors is manually opened, the other door will be automatically opened by the apparatus; third, to provide an apparatus of this class which assists in opening the doors after they are moved to certain positions in opening the same; fourth, to provide an apparatus of this class which is positioned up out of the way and does not interfere in any way with passing into and out of the garage; fifth, to provide a novel door control apparatus of this class; and, sixth, to provide an apparatus of this class which is very simple and economical of construction and installation, durable, easy to operate, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a top or plan view of my door control apparatus shown in relation with doors in opened position and showing them in such relation with a fragmentary portion of a garage, and showing by dotted lines the position of the links and crossbar when the doors are closed; Fig. 2 is a sectional view through 2—2 of Fig. 1; Fig. 3 is a perspective view showing a detailed fragmentary portion of the apparatus in its relation to one of the doors; Fig. 4 is a perspective view of the latch, and Fig. 5 is a perspective view of the link and spring supporting member.

Similar characters of reference refer to similar parts and portions throughout the several views of the drawings.

The crossbar member 1, crossbar member 2, support 3, link member 4, link member 5, spring 6, latch 7, link and spring support 8, releasing lever 9 and string 10 constitute the principal parts and portions of my garage door control apparatus.

The garage A is provided with a stop B 55 and with doors C and D all of the conventional swing double door type. Secured to the door D intermediate its sides is an L-shaped support 3 to which is pivotally connected the crossbar member 2 near one end. 60 This crossbar member 2 is preferably an L-shaped member in cross section and is adapted to extend only part way across between the two doors when open and adjustably connected thereto is the crossbar 1 which is preferably a flat bar and is held in certain relation thereto by means of U bolts 2^a, thus providing means for adjusting the length of the crossbar composed of members 1 and 2 for different width door openings. Pivotally connected to the crossbar 1 some distance from its free end are the link members 4 and 5. The other end of the link member 4 is pivotally connected to the under side of the garage door roof supports, while the other end of the link member 5 is pivotally connected to a support 8 which is an L-shaped member secured to the door C intermediate its sides. This member 8 is provided with an extended portion 8^a near one side which is provided with a hole 8^b adapted to receive one end of the spring 6, while the other end of the spring 6 is connected to the crossbar 1 between its end and the pivotal connection of the links 4 and 5, as shown best in Fig. 1 of the drawings. The free end of the crossbar 1 is adapted to rest in the notch 7^a in the latch member 7 when the doors are in the opened position, as shown in Fig. 1 of the drawings, thus holding the doors open as shown. This latch member 7 is secured near the upper side of the door and is provided on one upper side with an inclined bent over portion 7^b which serves as a guide for guiding the end of the member 1 into the notch 7^a with the opening of the doors. Pivotally mounted on this latch member 7 at the point 7^c is the release lever 9, the extended end of which is rounded and adapted to engage the under side of the free end of the crossbar member 1 and raise the same so that it will pass over the inclined portion 7^b and into the upper side of the garage with the closing of the doors, as shown by dotted lines in Fig. 1 of the drawings.

Though I have shown and described a particular construction, combination and arrangement of parts and portions, I do not wish to be limited to this particular construc-

tion, combination and arrangement but desire to include in the scope of my invention the construction, combination and arrangement substantially as set forth in the appended claims.

Having thus described my invention, what I claim as new and desire to secure by Letters Patent is:

1. In a garage door control apparatus, a crossbar pivotally connected to one of the doors, a link pivotally connected near the free end of said crossbar and its other end pivotally connected to the garage, another link pivotally connected to said crossbar near its free end and its other end pivotally connected to the other door, a latch on the latter door adapted to receive the free end of said crossbar, a spring secured to said crossbar and to one of the doors, and means for releasing said crossbar from said latch.

2. In a door control apparatus, the combination with double hinged doors, of a crossbar pivotally connected to one of said doors intermediate its sides, a link pivotally connected near the free end of said crossbar and its other end pivotally connected above and back of the door opening, another link pivotally connected to said crossbar near its free end and its other end connected to the other door, a latch on the latter door adapted to receive the free end of said crossbar, a spring secured to said crossbar at one end and its other end to said door, and lever means for releasing said crossbar from said latch.

3. In a door control apparatus, the combination with double hinged doors, of a longitudinally adjustable crossbar pivotally connected to one of said doors intermediate its sides, a link pivotally connected near the free end of said crossbar at its other end pivotally connected above and back of the door opening, another link pivotally connected to said crossbar near its free end and its other end connected to the other door, a latch on the latter door adapted to receive the free end of said crossbar, a spring secured to said crossbar at one end and its other end to said door, and lever means for releasing said crossbar from said latch.

4. In a garage door control apparatus, a longitudinally adjustable crossbar pivotally connected to one of the doors of the garage, a link pivotally connected near the free end of said crossbar and its other end pivotally connected to the garage, another link pivotally connected to said crossbar near its free end and its other end pivotally connected to the other door, a latch on the latter door adapted to receive the free end of said crossbar, a spring secured to said crossbar and to one of the doors, and means for releasing said crossbar from said latch.

5. In a door control apparatus, the combination with double hinged doors, of a bar pivotally connected at one end to one door

intermediate its sides, double link means connected to the opposite end of said bar connected at one end with the other door intermediate its sides, the other end pivotally connected back of the door opening, and latch means on said door adapted to engage said bar when both doors are open.

6. In a door control apparatus, the combination with double hinged doors, of a bar pivotally connected at one end to one door intermediate its sides, double link means connected to the opposite end of said bar connected at one end with the other door intermediate its sides, the other end pivotally connected back of the door opening, latch means on said door adapted to engage said bar when both doors are open, and spring means connected with said bar tending to draw said bar into said latch.

7. In a door control apparatus, the combination with double hinged doors, of a bar pivotally connected at one end to one door intermediate its sides, double link means connected to the opposite end of said bar connected at one end with the other door intermediate its sides, the other end pivotally connected back of the door opening, latch means on said door adapted to engage said bar when both doors are open, spring means connected with said bar tending to draw said bar into said latch, and lever means for releasing said bar from said latch.

8. In a door control apparatus, the combination with double hinged doors, of a bar pivotally connected at one end to one door at its inner side, double link means connected to the opposite end of said bar and also connected with the other door at its inner side and also connected to the frame of the opening for the doors, and latch means adapted to engage the last mentioned end of the bar.

9. In a door control apparatus, the combination with double hinged doors, of a bar pivotally connected at one end to one door at its inner side, and short double link means connected to the opposite end of said bar and also connected with the other door at its inner side and also connected to the frame of the opening for the doors immediately behind the opening.

10. In a door control apparatus, the combination with double hinged doors, of a bar pivotally connected to the inside of one of the doors, a short link pivotally connected near the opposite end of the bar and pivotally connected at its opposite end to the frame of the door opening immediately behind the opening, and another short link pivotally connected to the last mentioned end of said bar and also pivotally connected to the other door.

11. In a door control apparatus, the combination with double hinged doors, of a bar pivotally connected to the inside of one of the doors, a link pivotally connected near the

opposite end of the bar and pivotally connected at its opposite end to the frame of the door opening, another link pivotally connected to the last mentioned end of said bar and also pivotally connected to the other door, and a spring secured to the bar at the last mentioned end thereof beyond the piv-

otal connection with said links, the opposite end of said spring being connected to the last mentioned door.

10

In testimony whereof, I have hereunto set my hand at Los Angeles, California, this 14th day of June 1926.

JOHN A. ANDERSON.
